UNITED STATES PATENT OFFICE

CARRIE O. LONG, OF CHICAGO, ILLINOIS

HAIR WAVING APPLIANCE

Application filed June 11, 1929. Serial No. 370,127.

My invention relates to hair waving appliances and my main object is to provide a device of this kind which is composed of units having a cooperative function to create a succession of waves in the hair.

A further object of the invention is to build the units referred to in the nature of combs which are easily applied yet are of a form to cling to the hair and keep the same in waved condition.

A still further object of the invention is to design the combs with oblique teeth and arrange them consecutively with their teeth in opposite directions whereby to form the wave in the hair.

Another object of the invention is to combine with the array of units a frontal unit which serves in an opposite direction consistent with the slope of the hair.

20 A final but nevertheless important object of the invention is to provide the units in the appliance with interconnecting binding devices which retain the units against recession and thereby aid the appliance in holding its place.

With the above objects in view and any others that may suggest themselves from the specification and claims to follow, a better understanding of the invention may be had 30 by reference to the accompanying drawings, in which—

Figure 1 is a perspective view of the novel appliance as mounted on the hair; and

Fig. 2 is a perspective view of one of the 35 comb units forming part of the appliance.

Referring specifically to the drawings, 5 denotes one of the units employed in the novel appliance, the same being a comb comprised of an arched strip with teeth 6 projecting from one edge of the strip in the plane of the arch. As clearly shown in Figure 2, the teeth are deflected obliquely in the same general direction, the units being made in sets whose teeth slant in one direction and also in sets 40 whose teeth slant in the opposite direction.

When employing the units to make up the appliance, units of both sets are used in alternation as indicated in Figure 1. Thus, when the hair has been dampened and the units inserted in close succession, the effect will be

that the hair will be formed into waves because of the alternate obliquity of the succeeding units.

In the application of the units over the top and the back of the head it is essential that they be inserted with the teeth inclined in a forward direction; however, at the front the slant of the hair will require that one or two of the frontal units be inserted with the teeth in a rearward direction. Also, because of the 55 undesirability of waving the hair just above the forehead, the frontal unit or units which have their teeth projected in a straight direction instead of obliquely from the strip or base.

I prefer to mount the majority of the comb units with small buttons 7, widely spaced. These buttons are adapted to serve as securing means for rubber bands 8 from one comb to the next, my purpose being to have the 70 combs held to one another against the tendency for them to recede while the appliance is mounted or the wearer moves the head. It is not necessary that a large number of bands be employed, since but a few scattered at 75 points where laxity is found in one or another unit will combine to exert a sufficient hold upon the array of units to keep them closely fitted upon the hair. Also, the comb units have an inherent tendency to contract 80 or close, which aids them in holding their position as applied.

It will be seen that the novel appliance employs a comb unit of unique design, the same not only consisting of the band-like strips 5 which secure their hold upon the formation of the hair but also of the oblique teeth, which in alternation impart the waves to the hair. The securing bands 8 are necessary for the safeguarding of the units against recession and no special clamps or delicate appliances are used for securing the comb units. The appliance is therefore one which is made up of elements of extreme simplicity, and on account of this fact enables the average person to use the appliance without the aid of a 85 trained hairdresser.

I claim:—

1. A hair waving comb comprising a strip of material shaped to conform to the contour 90

- of the head and to extend from one side thereof to the other, said strip of material having a series of obliquely directed teeth formed integral therewith.
- 5 2. A hair waving comb comprising a strip of arched material to be positioned on the head so as to extend from one side thereof to the other, said strip of material having a series of teeth lying in the plane thereof.
- 10 3. A hair waving comb comprising a strip of material arched so as to extend from one side of the head to the other when operatively positioned thereon, said strip of material having a series of obliquely directed teeth lying in the plane thereof.
- 15 4. A hair waving appliance comprising a series of combs adapted to be arranged in series upon the head of a user, each comb being formed of a strip of arched material so as to extend from one side of the head to the other, said strip of material having a series of teeth integral therewith.
- 20 5. A hair waving appliance comprising a series of connected combs, each comb being formed of a strip of arched material so as to extend from one side of the head to the other, said strip of material having a plurality of obliquely disposed teeth lying in the plane thereof.
- 25 30 6. A hair waving appliance comprising a series of combs, means for connecting the combs comprising studs on the respective combs and elastics attached thereto, each comb formed of a strip of arched material so as to extend from one side of the head to the other, said strip of material having a plurality of obliquely disposed teeth lying in the plane thereof, the teeth of adjacent combs being disposed in opposite directions.
- 35 40 In testimony whereof I affix my signature.
CARRIE O. LONG.
